UNITED STATES PATENT OFFICE.

REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

PORTABLE PNEUMATIC DRILL.

SPECIFICATION forming part of Letters Patent No. 792,281, dated June 13, 1905.

Application filed July 20, 1904. Serial No. 217,371.

To all whom it may concern:

Be it known that I, REINHOLD A. NORLING, a citizen of the United States, and a resident of Aurora, in the county of Kane and State of Illinois, have invented certain new and useful Improvements in Portable Pneumatic Drills; and I do hereby declare that the following is a full, clear, and exact description thereof, reference being had to the accompanying drawings, and to the letters of reference marked thereon, which form a part of this specification.

This invention relates to improvements in portable pneumatic drills or mechanisms of that kind embracing a fluid-pressure engine of portable form applied to operate a drill or like tool.

Improvements constituting my invention are illustrated in the accompanying drawings as applied to a machine having four power-cylinders of the kind illustrated in United States Letters Patent No. 762,932, granted to me June 21, 1904; but my invention is also applicable to other machines of the same general character.

The invention consists in the matters hereinafter set forth, and more particularly pointed out in the appended claims.

In the accompanying drawings, illustrating my invention, Figure 1 is a sectional view of the machine embodying my invention taken through the central axis of the tool actuating or driving spindle and the crank-shaft of the motor. Fig. 2 is a view of the machine when seen from beneath with the bottom wall of the casing removed and the crank-shaft and driving-spindle in section, taken upon line 2 2 of Fig. 1. Fig. 3 is a detail view of the crank-shaft and bearing-plate to which my invention more particularly relates, the crank-shaft being shown in transverse section taken on a plane parallel with the bearing-plate and passing through the crank-pin of the crank-shaft, as indicated by line 3 3 of Fig. 1. Fig. 4 is a detail sectional view of the crank-shaft, taken upon line 3 3 of Fig. 1, but showing the crank-shaft separate from the other parts. Fig. 5 is a face view of

the bearing-plate separate from the other parts. Fig. 6 is a side view of said bearing-plate. Fig. 7 is a top or plan view of a disk or washer which carries the counterbalance-weight for the eccentric. Fig. 8 is a top or plan view of the eccentric. Fig. 9 is a sectional view of the same, taken upon line 9 9 of Fig. 8.

As shown in the said drawings, A indicates the main casing of the machine, which contains an air-supply chamber B and a crank-chamber C.

D D indicate the two cylinders constituting the lowermost pair of power-cylinders of the motor, and E, Fig. 1, indicates one of the power-cylinders of the upper pair of cylinders. The main casing A is provided at its side adjacent to the crank-shaft chamber B with a handle G, and a handle is formed on the opposite side of the casing by means of an air-supply pipe F, which communicates with and supplies air to the chamber B.

H indicates the crank-shaft, which extends through the crank-chamber C, and d e, Fig. 1, indicate connecting-rods, which are attached to the piston in the cylinders D and E and engage the cranks of said crank-shaft H. Said crank-shaft engages at its upper end a bearing I, supported in the top wall A² of the casing A at the top of the crank-chamber and at its lower end engages a bearing J, which is supported in a cap or auxiliary casing A', which is secured to what may be called the "lower face" of the main casing A.

K indicates the main driving-spindle of the machine, through which motion is transmitted to the rotative tool or other part to be driven. Said spindle extends through the bottom wall of the auxiliary casing A', having a bearing L therein, and at its upper end engages a bearing M, located within the casing. Said bearing M is supported by a wall or diaphragm A³, which forms the bottom of the air-supply chamber B. Mounted in the upper part of the casing in line with the driving-spindle K is a feed-screw N, which engages and passes through a sleeve N', secured in the top wall A² of the casing A and provided at

its upper end with handles n n , by which it may be turned.

The driving-spindle K is actuated from the crank-shaft H by means of a pinion H' on 5 said crank-shaft, which intermeshes with a spur-gear K' on the said spindle. The pinion H' is shown as formed by gear-teeth cut in the crank-shaft H , and said pinion and the gear-wheel K' are located below the bottom 10 wall A^3 of the main casing A and within the auxiliary casing A' , which latter covers said parts as well as the devices by which the valves for controlling the passage of pressure fluid to and from the cylinders are actuated from 15 the crank-shaft, said devices being located within the said casing A' between said pinion H' and gear-wheel K' and the adjacent lower wall A^3 of the casing A .

O O indicate rock-shafts through which 20 motion is given to the oscillating cylinder or plug-valves of the engine. Said rock-shafts are supported or have bearing in the caps O O' , which close the ends of the valve-chambers. Attached to the rock-shafts O O are 25 crank-arms O^2 O^2 , with which are connected the ends of eccentric-rods P P' . The straps p p' of said eccentric-rods are engaged with a double eccentric Q , which surrounds the crank-shaft H above the pinion H' and is 30 driven from said crank-shaft.

My present invention relates more particularly to means for affording an intermediate or auxiliary bearing for the crank-shaft H and for supporting and driving the eccentric 35 Q , and these features are made as follows:

R indicates a bearing-plate which is held or clamped at its margins between the parts A A' of the casing and is provided with an integral bearing-sleeve R' , which is arranged 40 concentrically with and surrounds the shaft H between the pinion H' and the cranks of the crank-shaft. Said sleeve R affords a bearing both for the said crank-shaft H and the eccentric Q . The sleeve R' is provided with 45 a bushing r , in which the crank-shaft turns, while the eccentric Q fits and turns upon the exterior cylindric surface of the said sleeve.

As a preferable means for securing the plate R in place within the casing the parts or sections A A' of the casing are divided on a plane adjacent to the plane of said plate, so that the joint between said parts comes into position to receive the outer margin thereof, and the said parts A A' of the casing are shaped to 55 provide at the joint between them a groove or recess adapted to receive the marginal part of said plate.

In the particular construction illustrated 60 the upper part of the crank-chamber C is cylindric in form, and the lower part of the external wall of the casing A , which forms the lower part of the outer wall of the said crank-chamber, has the form of a segment of a circle, as clearly seen in Fig. 2. That portion A^4 of 65 the lower or cap portion A' of the casing into

which the lower end of the crank-shaft extends is of like form and is provided at its upper margin with an outwardly-extending flange a , Fig. 1, which fits against the lower margin of the main port of the crank-chamber wall and is secured thereto by headed bolts a' , which pass through said flange a and enter the marginal part of the said crank-chamber wall above it. Said lower margin of the main crank-chamber wall is provided 70 with a rabbet or recess adapted to receive the marginal part of the plate R , which in its part which engages said crank-chamber wall is shaped to conform to a circular curve and to correspond with the shape of the said 75 crank-chamber wall, as clearly seen in Fig. 2. The upper margin of the port A^4 of the cap A' of the casing, together with its flange a , is adapted to fit against the lower margin of the crank-chamber wall and to also overlap 80 and fit against the marginal part of the said supporting-plate R . When the parts of the casing are clamped and secured together, therefore, the marginal part of the said plate R will be rigidly held or secured in place by 85 being confined between the meeting margins of the main part A and cap A' of the casing. 90

As shown in the drawings and as preferably constructed, the bolt-holes for the bolts a' will be arranged along the line of contact 95 between the margin of the plate R and the casing-wall, as clearly seen in Fig. 2, so that the said holes extend partially into the margin of said plate. As an additional means of centering or holding rigid in place the plate 100 R , the same will preferably be provided with a depending concentric flange or rib r' , adapted to enter and engage the inner surface of the port A^4 of the cap A' , which port A^4 is smaller in size or diameter than the main 105 part of the crank-chamber above it.

Now referring to the means shown for affording a driving connection between the crank-shaft and the eccentric Q , said eccentric is provided at its upper margin, or its 110 side nearest the adjacent crank-arm h of the crank-shaft H , with a driving lug or stud S , Figs. 8 and 9, which engages a radial slot or notch H^2 , formed in the said crank-arm h , which latter preferably has the form of a flat 115 plate and is extended laterally to constitute arms h' h'' , between which said slot H^2 is formed. The stud S may be secured in any convenient way to the eccentric; but in the particular construction shown it consists of 120 a flat-sided block provided with a cylindric stem s , which enters a hole formed in the eccentric to receive it.

The stud S is not designed to be fitted 125 closely in the slot H^2 , but is loosely engaged therewith in such manner as to have a slight radial movement therein. Such loose connection of the stud S with the crank-arm H is designed to insure the smooth running of 130 the parts in cases where, through wear or

some other cause, the crank-shaft is not exactly concentric with the exterior bearing-surface of the sleeve R', on which the eccentric turns. As a result of the construction 5 described the eccentric will always rotate on its own bearing on the sleeve R uninfluenced by any slight eccentricity of the crank-shaft H which might occur through wear or imperfect fitting of the parts.

- 10 T in the drawings indicates a counterbalance-weight which is attached to the crank-arm H to counterbalance the eccentric and insure the smooth running of the parts. As a means of attaching said weight T to the 15 crank-shaft, a plate or disk T' is employed which is provided with a central aperture to receive the crank-shaft H and which fits against the under surface of the crank-arm h, between said crank-arm and the eccentric. 20 Q. Said disk T' is provided with a radial slot T², which coincides in position with the radial slot H² of the crank-arm h and through which passes the stud S on the eccentric. The counterbalance-weight T is located in 25 the same plane with the arm h and fits against the margin or edge thereof, said counterbalance-weight being secured by means of screws or otherwise to the marginal part of the plate or disk T', which projects 30 outside of or beyond the said arm h, as clearly seen in Figs. 1, 3, and 7.

A general advantage obtained by the use 35 of the bearing-plate R, attached to or supported from the casing in the manner described, is that such bearing-plate affords a lateral bearing or support for the crank-shaft at a point between the driving-pinion and said cranks, so as to prevent any springing or flexure of the shaft when in operation and to 40 insure the smooth running of the parts. The advantage gained by mounting the eccentric Q on the plate R is that said eccentric is thereby supported on a bearing which is rigidly attached to the casing and will maintain 45 its position notwithstanding any wearing of the crank-shaft bearing such as would per-

mit lateral shifting of said shaft from its normal position.

I claim as my invention—

1. The combination with a crank-shaft, of 50 a bearing-plate provided with a rigidly-attached bearing-sleeve and a valve-actuating eccentric mounted on said sleeve.

2. The combination with a crank-shaft, of 55 a bearing-plate provided with a rigidly-attached bearing-sleeve, and a valve-actuating eccentric mounted on said sleeve, and loosely-connected interlocking parts on the said eccentric and on the crank-shaft by which said eccentric is driven from the crank-shaft. 60

3. The combination with a crank-shaft, of 65 a bearing-plate provided with a rigidly-attached bearing-sleeve, a valve-actuating eccentric mounted on said sleeve, and driving connections between the said eccentric and the crank-shaft consisting of a stud on the eccentric and a radial slot formed in one of the crank-arms of the crank-shaft and adapted to receive said stud on the eccentric. 75

4. The combination with a crank-shaft, of 70 a bearing-plate provided with a rigidly-attached bearing-sleeve, driving connections between the said eccentric and the crank-shaft consisting of a stud on the eccentric and a radial slot formed in one of the crank-arms of the crank-shaft and adapted to receive said stud on the eccentric, a counterbalance-weight for the crank-shaft, and a disk to which said weight is attached, said disk being located on the crank-shaft adjacent to the eccentric and provided with a slot through which passes the said stud on the eccentric. 80

In testimony that I claim the foregoing as my invention I affix my signature, in presence of two witnesses, this 13th day of July, 85 A. D. 1904.

REINHOLD A. NORLING.
